UNITED STATES PATENT OFFICE.

MARK G. MELVIN, OF SCRANTON, PENNSYLVANIA.

HOOD.

1,080,468.

Specification of Letters Patent.

Patented Dec. 2, 1913.

Application filed March 7, 1913. Serial No. 752,749.

To all whom it may concern:

Be it known that I, MARK G. MELVIN, a citizen of the United States, residing at Scranton, in the county of Lackawanna and 5 State of Pennsylvania, have invented new and useful Improvements in Hoods, of which the following is a specification.

This invention is an improved hood for use in the roof of a railway station to afford 10 a vent for the escape of smoke and steam from the smoke stacks of the locomotives under the roof and to also prevent rain and snow from entering, the invention consisting in the construction, combination and 15 arrangement of devices hereinafter described and claimed.

In the accompanying drawing:—Figure 1 is a perspective view of a portion of a railway station provided with hoods constructed in accordance with my invention. Fig. 2 is a detail vertical transverse sectional view of the same. Fig. 3 is a detail vertical longitudinal sectional view of the same. Fig. 4 is a detail transverse sectional view, 25 showing a modified form of the hood.

In accordance with my invention, the roof 1 of a railway station which may be otherwise of any suitable construction, is provided with a longitudinal opening 2 of 30 suitable width above the center of each track so that the upper end of the smoke stack of a locomotive on that track will be directly under the said opening and the latter will afford vent for the steam and smoke from 35 the locomotive and, hence, prevent steam and smoke from being dispersed throughout the station under the roof. In order to prevent rain from entering the said opening, I provide a hood 3 which is coextensive in 40 length with the said opening and is placed on the roof at a point immediately above the opening, the walls of the hood, indicated at 4, having outturned base flanges 5, which bear on the roof and are secured thereto as 45 by means of suitable screws or bolts 6. The upper portion of the hood is bent or deflected to one side as at 7 to form the mouth of the hood and cause the smoke and steam from the locomotive to be discharged into

the air and also to prevent rain from entering 50 the hood, and hence, finding its way down through the opening 2.

The hood is provided at suitable points with braces 8 between its walls and is also provided at its mouth with doors or flaps 55 9 which are hingedly mounted as at 10, at points near their upper sides and which by gravity dispose themselves in vertical closed position so that ordinarily the mouth of the hood is closed at all points. The pivotal axes of the doors or flaps of the mouth of the hood are somewhat below the extreme upper sides of the said doors or flaps so that the latter are rendered sensitive to pressure from within and, hence, the doors or flaps 60 65 which are near a locomotive smoke stack under the roof will be caused to open by the pressure of the escaping steam and smoke from the locomotive and, hence, afford vent therefor. While these doors or flaps are free 70 to swing outwardly to afford vent for the smoke and steam from a locomotive, they are prevented by suitable stops 11 from swinging inwardly and, hence, are normally closed. The roof is, in practice, provided 75 with suitable spouts 12 in depressed portions to carry off the rain water.

While I have herein shown and described a preferred form of the invention, I would have it understood that changes may be 80 made in the form, proportion and construction of the several parts without departing from the spirit of the invention and within the scope of the appended claims.

I claim:—

1. A train shed roof having a longitudinal opening above the track and a hood extending up from said opening and having a laterally deflected discharge portion and flaps in the discharge portion of the hood 90 opening to pressure from within and closing to pressure from without.

2. A train shed roof having an opening above the track and also having a hood extending upwardly from said opening and 95 provided with flaps opening to pressure from within and closing to pressure from without.

85

3. A train shed roof having an opening above the track and also provided with a hood extending up from said opening, the said hood having side walls provided with base flanges bearing on the roof on opposite sides of the opening and also having a laterally extending discharge mouth.

In testimony whereof I affix my signature in presence of two witnesses.

MARK G. MELVIN.
